UNITED STATES PATENT OFFICE.

JOHN POYSER, OF WIRKSWORTH, ENGLAND.

BATTEN FOR WEAVING-LOOMS.

SPECIFICATION forming part of Letters Patent No. 635,805, dated October 31, 1898.

Application filed November 28, 1898. Serial No. 697,656. (No model.)

To all whom it may concern:

Be it known that I, JOHN POYSER, a subject of the Queen of Great Britain, residing at Wirksworth, near Derby, England, have invented new and useful Improvements in or
5 Connected with Battens for Weaving-Looms, (for which I have applied for a patent in Great Britain, No. 10,499, dated May 7, 1898, and in Germany, No. 98,511/86, dated June 8, 1898,) 10 of which the following is a specification.

This invention relates to battens for weaving-looms and to means for operating the same, and more particularly to battens having oscillating upper and lower parts of the 15 kind described in the specification of a former patent granted to me, No. 566,222. In the arrangement of batten described in the said former specification a spring is employed for holding the upper part of the batten back or 20 away from the fell of the fabric, except when the said upper part is carried forward by the stroke of the lower part.

The object of this invention is to dispense with the spring and thereby obviate the strain 25 and vibration caused by the action of the said spring when the loom is working at a high rate of speed, and to this end I provide for operating the two parts of the batten positively in both directions by means of oscillating or revolving cams, or I may use a single cam, which operates one part of the batten, the other part being operated through the medium of a movable connecting piece or block having rollers, which extend into 30 slots formed in the two parts of the batten, which slots are so shaped that when, say, the lower part of the batten is operated by the cam the slot therein will move the connecting-piece, which will in its turn act in the slot in 35 the other part of the batten and move it in the desired manner.

To enable my invention to be fully understood, I will describe the same by reference to the accompanying drawings, in which—

45 Figure 1 is a longitudinal section of part of a loom of the kind described in the specification before referred to and having the two parts of the batten driven by independent cams; and Fig. 2 is a section on the line 2/2 of 50 Fig. 1, looking in the direction of the arrow in the said figure. Fig. 3 is a sectional view of a portion of the mechanism detached. Fig.

4 is a rear elevation, drawn to a larger scale than Figs. 1 to 3, illustrating the arrangement wherein only one part of the batten is driven by a cam, the other part being operated through the medium of a connecting-piece. Fig. 5 is a side elevation of the same. Fig. 6 is a view similar to Fig. 4, but showing the parts in a different position. Figs. 7 and 8 60 are side views of the upper and lower parts, respectively, of the batten detached.

Similar letters of reference indicate corresponding parts throughout the drawings.

a is the lower part of the batten, which is 65 fixed to the shaft b; Figs. 1 and 2, and oscillated from the cam c through the medium of the arm c', fixed to the shaft b and the rod d in the manner described in the specification before referred to, and e is the upper part of 70 the batten, which is loosely mounted upon the shaft b and formed with an arm f, as clearly shown in Fig. 3, to which is connected one end of a rod g, the other end of which is acted upon by a cam i on the main driving-shaft. 75

It will be noticed by reference to Fig. 2 that the cams c i are in the form of grooves, in which rollers j j, near the lower ends of the rods d g, run, the lower ends of the rods being bifurcated, so as to embrace the driving-shaft, which thus forms a guide for the lower ends of the said rods. The cam-grooves c and i must be of such shape and arranged in such relation to each other that the cam c will move forward the lower part of the batten until its 80 dents coincide with those of the upper part, which in the meantime has remained at rest, in order that the two parts of the batten may then move together from this position to beat up the weft laid in front of the batten and 85 then return, the upper part e first coming to rest and the lower part being then moved farther back to open the batten to allow the passage of the weft-finger of the shuttle for laying another weft, and so on. 90

In Figs. 4 to 8, which illustrate the arrangement wherein one part of the batten is positively driven from the other part through the medium of a connecting-piece, k l are the slots formed in the parts a and e of the batten, respectively, and m is the connecting-piece, which is in the form of a lever or arm pivoted to some suitable part of the frame of the machine and having at its free end a pin 95

n, carrying two antifriction-rollers *o p* in the slots *k l*, respectively. These slots are of the same shape, except that the slot *k* has an extension *k'*, which is concentric with the axis 5 of the shaft *b*. The slot *l* and the part of the slot *k* of similar shape coincide with one another when the two parts of the batten are closed together, as shown in Fig. 5, so that when motion is imparted to the batten part 10 *a* in a backward direction—that is to say, in the direction of the arrow, Fig. 5—the pin *n* being acted upon by the slot *k* acts in turn upon the slot *l* and causes the part *e* of the batten to move with the part *a* until the roller 15 *p* reaches the upper end of the slot *l*, when the motion of the batten part *e* stops. As, however, by this time the extension-slot *k'* in the batten part *a* is opposite the roller *o* the motion of the said batten part *a* can continue 20 its movement in order to form the opening between the two parts of the batten, as shown in Fig. 6. During the forward movement of the batten part *a* the movements are reversed—that is to say, the batten part *a* first

moves independently and then the two parts 25 move together.

Having now particularly described and ascertained the nature of my said invention and in what manner the same is to be performed, I declare that what I claim is—

30

1. A batten for looms formed of two parts having a common pivotal point with means for operating both parts positively to close them together, beat up the weft and again open them, substantially as described.

35

2. A batten for looms composed of two parts, said parts being positively operated, a cam for transmitting motion to one part of the said batten and a connecting-piece working in slots in the said two parts of the batten and serving to transmit positive motion from the part operated by the cam to the other part, substantially as described.
